UNITED STATES PATENT OFFICE

FRANK H. HOPKINS, OF ALEXINGTON, AND FRANK B. WOODMAN, OF WORCESTER, MASSACHUSETTS, ASSIGNEES, BY MESNE ASSIGNMENTS, TO CONSOLIDATED ASHCROFT HANCOCK COMPANY, INC., OF NEW YORK, N. Y., A CORPORATION OF DELAWARE

INCASED ADJUSTABLE WEIGHT-LOADED VALVE

Application filed December 10, 1925. Serial No. 74,568.

The present invention relates to valves and to equipment including valves. More particularly it is concerned with a valve adapted to prevent siphonic action in a pipe system through which liquid is conducted, and means for applying a weight to such a valve with tendency to close it, but in a manner such that the effective force applied by the weight may be varied and adjusted at will, and also that the weight may be wholly increased in a structure of relatively small volume and protected by its casing from being accidentally shifted out of adjustment. The invention comprises such a valve, and the combination thereof with a liquid-conducting pipe system, as more particularly set forth in the following specification, and as embodied in other structures substantially equivalent to that described in said specification.

Without intending thereby to indicate any limitation in the nature of the invention, or of the protection which we claim for it, we may say that one conspicuous field of use for which it is adapted is that of an anti-siphon valve in oil burning equipment in order to prevent continued flow of oil by siphonic action, when the normal oil feeding means ceases to function, whether accidentally or by design. Such continued flow is liable to flood the furnace base or furnace room with oil, with consequent danger of a disastrous fire, particularly in connection with oil burning equipment used for domestic purposes, which is designed to run with a minimum of personal attention. This liability arises in situations where the burner is fed by a pump and is at a lower level than the supply tank, when the action of the pump is interrupted, unless automatic means are provided for then closing the siphonic supply line. Heretofore, in such situations, there have been used for this purpose anti-siphon valves of two types, one type being weight-loaded, and the other being spring-loaded, so as to be closed when the suction of the burner feed pump ceases and when the only suction applied is that due to the head of oil in the descending leg of the siphonic pipe leading from the supply tank to the burner.

The difficulty with spring-loaded anti-siphon valves is that the springs used are liable to break or become weakened or distorted with extended service so much as to be incapable of closing the valve against the siphonic suction head. The weight-loaded valves heretofore used, while not subject to this defect, are nevertheless liable to be accidentally disarranged and put out of adjustment, and they occupy so much space that frequently they cannot be installed in positions where they would be safe from liability of being disarranged and put out of adjustment.

The new step which we have made with the present invention is to provide, for the combination and use above referred to, and other combinations and uses, a new construction of valve which is weight-loaded with closing tendency, and is also equipped with a spring and with adjusting means for varying the effective closing effort exerted by the weight, and the whole structure is compact and small in bulk, and the movable and adjustable parts, including the weight, are all encased in such fashion as to be immune from accidental disarrangement.

We will now describe the invention in detail, in relation to the particular use of an anti-siphon valve in oil burning apparatus and with reference to the drawings provided with this specification.

In the drawings,—

Figure 1 is a diagrammatic view illustrating a domestic oil burner installation having our invention applied thereto;

Figure 2 is a sectional view showing the preferred form of valve in detail.

Referring to the diagram, *a* represents a casing in which is an oil burner. Such casing may be a furnace or heater of any sort, designed to heat water or generate steam for house heating or other purposes, and located in the common location for domestic oil burners; that is, in the cellar or basement of a building and below the ground level which is represented at *b*. *c* represents a supply tank for oil buried in the ground outside of the basement wall, and wholly or partially above the level of the oil burner. The usual tank

filling tube is shown at *d* and vent tube at *e*. The pipe line for conducting oil from the tank to the burner consists of a section *f* rising from the bottom of the tank to a level 5 above its top, a section *g* leading from the section *f* through the basement wall into the furnace room, and a descending section or leg *h* within the cellar, extending in any convenient course to the feed pump, by which oil 10 is drawn from the tank and delivered under the desired pressure to the burner: *i* represents an anti-siphon valve between the pipe sections *g* and *h*, adapted to be opened so as to permit flow of oil when the feed pump is in 15 operation and to be closed and prevent oil flow under the siphonic action of the column of oil in the pipe or leg *h*, when the pump is stopped. It will be appreciated that the pipe sections *f*, *g* and *h* form a siphon, of which 20 the longer leg *h* is inside the building and is liable to deliver a flood of oil unless siphonic action be checked.

Referring now to Figure 2 for a detailed illustration of the novel and improved valve 25 which embodies this invention, said valve comprises a body 1 having an upright lower branch 2 and a lateral branch 3, in each of which are passages for flow of liquid. Surrounding the upper end of the passage in 30 the upright branch 2 is a seat 4, on which is seated the valve proper 5, said valve proper having a guiding stem 6 formed with wings, entering the upright passage in a manner common in this art. The pipe line *g* is connected by an upwardly turned fitting or connection with the branch 2, and the descending leg *h* is connected by a suitable fitting or coupling with the lateral branch 3. Hence the oil pressure induced by the feed pump or by 35 siphonic action tends to unseat the valve proper.

For loading the valve, we provide a weight 40 which rests on the valve proper, preferably having a stem 8 entering a recess in the valve proper and having a bearing area of limited extent at the bottom of such recess, as shown in the drawing. This weight is enclosed partly by the valve body 1 and partly by a cover 45 casing 9, which is detachably screwed into the valve body, these two members together forming a casing which completely encloses the weight without limiting its freedom of movement or that of the valve proper.

A stem 10 passes through the upper wall 50 of the cover 9, with which it has a screw threaded engagement. Its lower end, provided with an enlarged head 11, is contained in a deep pocket or chamber 12 in the weight. A spring 13 surrounds the stem 10 and is confined between the head 11 and a plug 14, 55 screwed into the threaded upper end of the chamber 12 and having a central guideway through which the stem 10 passes freely. Said head and plug provide abutments for 60 the spring, the former of which abutments

is connected with the casing and the other with the weight. A lock nut 15 is screwed on the protruding end of the stem 10 outside of the cover 9; and a protecting cap 16 is screwed on to the extremity of the stem and encloses 70 the lock nut.

It will be readily appreciated from the foregoing description that the spring 13 exerts a lifting effect on the weight and that this effect may be either increased or diminished by appropriately shifting the head 11 by screwing the stem 10 in or out. Any adjustment so made is made permanent by setting up the lock nut 15, and turning back of the stem is then made impossible by applying the cap 16. Such cap, as it bears against the end wall of the cover 9, acts also as a second lock 80 nut.

The mass of the weight and the strength of the spring are appropriately designed with 85 reference to the siphonic head which the weight has to overcome, the area of the passage covered by the valve proper, and the suction capable of being developed by the feed pump. In any case, the weight is made 90 amply heavy to close the valve when the only tendency to open it is that caused by the siphonic effect of the pipe line; while the spring is made stiff enough so that, by adjustment, it may diminish the effective force of 95 the weight in the measure needed to cause opening of the valve by the suction of the pump and closing by the superior force of the weight when the pump is stopped. In such circumstances of use as that herein described, the unbalanced oil column in the descending pipe leg *h* is at any time relatively 100 short in comparison with the oil head equivalent to the atmospheric pressure; wherefore it is a simple matter to apply the principles 105 of this invention in designing a valve having a weight of suitable mass and a spring of suitable strength and stiffness for the purpose in view, and a single design of valve may be made which is capable of use in different situations wherein there are considerable 110 variations in the differences of level between the burner and the oil in the supply tank.

Considering other possible uses of this 115 invention, it will be evident that the same principles may be applied to any situation where the unbalanced liquid head tending to cause siphonic action is enough less than the suction head obtainable by a pump to permit of the weight being lifted when the pump 120 acts, and being closed by gravity when the unbalanced head of liquid in the siphon pipe alone acts. Preferably, the spring used is one which may be contained, without being compressed, between the head 11 and the abutment 14 when these parts are most widely 125 separated, and will be strong enough to support the weight without being compressed so far as to bring the coils together; that is, the spring should be capable of resiliently 130

- supporting the weight. However, this statement is one of preference merely and is not a limiting factor. Again, the spring is preferably one of helical formation properly proportioned to surround the stem 10 and to occupy the cavity in the weight, without making contact with either except on the abutments at the opposite ends of the helix; although other forms of spring may be used.
- 10 Ample space is left within the casing and around the weight to permit free rise and descent of the liquid in the casing without disturbance of the weight; and there is a drain passage 17 from the bottom of the chamber 12 to permit free flow of the liquid into and out of the chamber.
- 15 By virtue of the characteristics embodied in this valve as herein described, gravity tends constantly to close the valve by means of the weight, with a force superior to that of the spring. Hence in case of distortion, weakening or breakage of the spring, the closing tendency is increased rather than diminished or destroyed, (as is the case with spring-loaded valves); wherefore there is no danger 20 of the valve failing to close the pipe line when necessary. On the other hand, the application of the spring in the manner herein disclosed enables the effective force of the weight 25 to be adjusted as readily as in the case of any other weight-loaded valve, but the weight is protected from being accidentally displaced and put out of adjustment, and is arranged and combined with the casing in a 30 most compact way.
- The valve proper used in the construction here shown has an annular chamber 18 on its under side, outside of the seating surface, and a lip 19 surrounding said chamber, thus comprising means for causing the valve to open 35 and close completely and quickly, after the manner of a pop safety valve.
- As the principles of the invention may be embodied in other forms and applied in other 40 situations than as here shown, we do not limit our protection to the specific form of valve and combination here shown, or otherwise than according to the meaning of the appended claims as construed with reference 45 to the prior art.
- 50 What we claim and desire to secure by Letters Patent is:
1. A valve comprising a casing having inlet and outlet passages, a valve proper arranged to seat over the communication between said passages, a weight contained within said casing and arranged to exert pressure on said valve, a spring arranged to exert force on said weight in opposition to the force of gravity, and means for so adjusting said spring as to alter the force exerted by the weight on the valve.
  2. A valve comprising a casing having inlet and outlet passages, a valve proper arranged to seat over the communication be-
- tween said passages, a weight contained within said casing and arranged to exert pressure on said valve, a spring arranged to exert force on said weight in opposition to the force of gravity, and an abutment on which said spring reacts, said abutment being adjustable so as to alter the force exerted by the spring. 70
3. A valve comprising a casing having a rising inlet passage in its bottom and having also an outlet passage, a valve proper arranged to seat across said inlet passage, a weight contained within said casing resting on the valve proper and having a chamber extending downward from its upper end, a stem extending from the top of the casing downward into said chamber and having a head on its lower end, an abutment plug set into the upper part of said chamber, and a spring confined between said head and the plug, said stem being adjustable up and down to vary 75 the force exerted by said spring. 80
4. A valve comprising a casing, a valve proper within said casing, a weight also within said casing resting on said valve proper and in substantially vertical co-axial alignment therewith, an adjustable spring abutment supported from the casing, and a spring supported by said abutment and acting upwardly on said weight. 85
5. A valve comprising a casing, a valve proper within said casing, a weight also within said casing resting on said valve proper and in substantially vertical co-axial alignment therewith, a spring abutment adjustably supported from the casing with provision for 90 vertical displacement, and a spring reacting on said abutment and acting upwardly on the weight, the abutment and spring being also in substantially co-axial vertical alignment with the valve proper and the weight. 95
6. The combination with a siphonic pipe line of an anti-siphon valve in said pipe line, said valve including a weight under gravity impulsion tending to close the valve, a spring exerting a counterforce on said weight, means 100 for adjusting the counterforce exerted by said spring, and a casing enclosing the weight, spring and spring adjusting means. 110
- In testimony whereof we have affixed our signatures.
